UNITED STATES PATENT OFFICE.

HARRY A. FRANK, OF CHICAGO, ILLINOIS.

CUFF-PROTECTOR.

No. 879,955.

Specification of Letters Patent.

Patented Feb. 25, 1908.

Application filed October 26, 1907. Serial No. 399,273.

To all whom it may concern:

Be it known that I, HARRY A. FRANK, citizen of the United States, residing at Chicago, in the county of Cook and State of Illinois, 5 have invented a certain new and useful Improvement in Cuff-Protectors, of which the following is a full, clear, concise, and exact description, reference being had to the accompanying drawings, forming a part of this 10 specification.

My invention relates to devices for preventing the soiling of cuffs and lessening wear upon the edges thereof, and is of particular service in connection with cuffs that are permanently attached to shirts, though the invention is not to be restricted to this utility.

I am aware that it is old to provide cuff protectors having a purpose similar to the purpose of my present invention, but I have 20 never seen any of these cuff protectors of the prior art in actual service, the reason for which being, as I verily believe, that the cuff protectors hitherto devised are so constructed as not readily to permit the application 25 thereof to the cuffs and even after application these cuff protectors are not with certainty adapted to retain engagement with the cuffs. In the devices of the prior art the cuff protectors are formed of some resilient material, 30 such as celluloid, a strip of such material being folded so that it may overlie the edge of the cuff and rest against the contiguous portions of the inner and outer surfaces of the cuff. In these prior devices the resiliency of 35 the material of which the protector is made is such and the proximity of the walls of the protector is such that these walls have to be spread apart in order to permit of the insertion of the cuff, the protector thereafter holding 40 itself in position upon the cuff by its resiliency. Though the intention is to have the cuff protectors of the prior art hold themselves in place upon the cuffs due to their resiliency, yet, in practice, it is difficult thus 45 to secure the engagement of cuffs to the cuff protectors, and it is, furthermore, quite difficult to secure the insertion of the cuffs within the protectors.

In accordance with my invention, the cuff 50 protector is desirably made of some suitable transparent material, as sheet celluloid, though I do not wish to be limited to the material of which the device of my invention is made. The sheet or strip of material out of

which the protector is made is folded over to 55 constitute two protector walls, care being taken that the walls of the protector are sufficiently far apart or divergent to permit of the entry of a cuff therebetween, so that it will not be necessary to pry or force the walls 60 of the protector apart in order to secure the desired entry of the cuff. In order that the cuff protector may be held in position, I attach thereto fastening means adapted to engage a cuff portion, so as to hold the cuff well 65 within its protector. In order that the device of my invention may be adaptable to different widths of cuffs, the fastening means in question is desirably extensible and contractible. In the preferred embodiment of 70 the invention, the fastening means preferably includes a hook adapted to be inserted beneath the inner or concealed edge of the cuff, which hook is united with the protector by means of some extensible and contractible 75 connector, such as a coil spring.

I will explain my invention more fully by reference to the accompanying drawing, showing the preferred embodiment thereof, 80 in which—

Figure 1 is a perspective view of the device before its application to a cuff. Fig. 2 shows the same device as applied to a cuff. Fig. 3 is an enlarged sectional view through the point of attachment of the link mechanism 85 with the cuff protector on an enlarged scale.

Like parts are indicated by similar characters of reference throughout the different figures.

The cuff protector includes in its formation a sheet of some suitable material, preferably transparent and preferably celluloid, folded back upon itself so as to be of U-shape in cross-section, whereby there is afforded an inner wall *a* and an outer wall *b*, the base of the fold *c* engaging the outer edge of the cuff *d* to be protected, the inner and outer walls *a* and *b* being of sufficient width to extend a sufficient distance along the width of the cuff to protect the cuff against soiling, and, incidentally, against wear. The walls *a* and *b* of the protector are spaced a sufficient distance apart so that the cuff *d* may find free access to the space between said walls. In order that the protecting folded sheet may be retained in place after it has been easily slipped upon the cuff, I provide the retaining or anchoring means illustrated, which preferably include 90

95

100

105

two devices each having a hook *e* desirably formed of strip metal and adapted to be inserted beneath the inner or concealed edge of the cuff and having connection with the protecting sheet of material by means of the extensible and contractible link *f*, preferably a coil spring united at one end with the extension *e*¹ of the hook and united at the other end with an eyelet *f*¹ placed in the celluloid. 5
10 There need be but two of the fastening devices placed sufficiently close to the ends of the protector. The hooks *e* are desirably formed of strip metal, and in addition to the extension *e*¹ that is provided for the attachment of the spring *f*, there is also provided an opposite extension *e*² that constitutes a thumb and finger piece that enables the hook to be grasped and withdrawn from its engagement with the cuff and which is a help 15 to the guidance of the hook into engagement with the cuff. The hook portion proper is struck up from the middle portion of an integral strip of metal, whereby a rounded edge is offered to the shirt sleeve to avoid undue 20 wear upon the shirt sleeve.

I am also aware that it is old to provide clips which are slipped over the outer edge of the cuff and which have spring clamping engagement with the cuff and with the protector. This construction is objectionable 30 because the lodgment of the protector upon the cuff is not thereby assured and the engagement of the cuff therewith and of the protector therewith is difficult.

35 In the device of my invention, the cuff is confined between the hook and the protector, the spring connection between the hook and the protector holding the protector with sufficient firmness upon the cuff; the 40 cuff, so to speak, being under compression between both of its edges, due to the spring, in this way assuring the permanent lodgment of the protector upon the cuff. In other words, the cuff is held between the 45 hooks and between the base *c* of the protector, there being thus an anchorage at both edges, the spring mechanism preventing the protector from moving forward and preventing the hooks from moving backward. My 50 device thus comprises, in its preferred form, a cuff protecting device including a sheet of transparent material folded back upon itself to constitute two protecting walls, between which a cuff may be interposed, hook mechanism adapted to engage the inner edge of 55 the cuff, and extensible and contractible link mechanism uniting the hook mechanism and the folded sheet, said link mechanism serving to press the cuff protecting device, where 60 folded back upon itself, against the outer edge of the cuff, said cuff protecting device being thus afforded two places of anchorage upon the cuff, namely, the outer edge of the cuff where the fold of the cuff protector is

engaged and the inner edge of the cuff, where 65 the extensible and contractible link mechanism is engaged; the sheet of material being curved so as to be adapted to the shape of a cuff, the outer and inner layer of the cuff protector each having opposed edges extending 70 across the cuff protector and adjacent to the meeting edges of the cuff.

Having thus described my invention, I claim as new and desire to secure by Letters-Patent:—

75

1. A cuff protecting device including a sheet of material folded back upon itself to constitute two protecting walls, between which a cuff may be interposed, hook mechanism adapted to engage the inner edge of 80 the cuff, an extensible and contractible link mechanism uniting the hook mechanism and the folded sheet, the hook mechanism including a hook formed of strip metal, from the central portion of which the hook proper is 85 struck, an extension *e*¹ projecting from this hook forward for the attachment of the extensible and contractible link mechanism, and an extension *e*² extending backward from the hook to constitute a thumb and finger 90 hold.

2. A cuff protecting device including a sheet of transparent material folded back upon itself to constitute two protecting walls, between which a cuff may be interposed, 95 hook mechanism adapted to engage the inner edge of the cuff, and extensible and contractible link mechanism uniting the hook mechanism and the folded sheet, said link mechanism serving to press the cuff protecting device, where folded back upon itself, against the outer edge of the cuff, said cuff protecting device being thus afforded two places of anchorage upon the cuff, namely, the outer edge of the cuff where the fold of the cuff protector is engaged and the inner edge of the cuff, where the extensible and contractible link mechanism is engaged; the sheet of material being curved so as to be adapted to the shape of a cuff, the outer and inner layer of the 105 cuff protector each having opposed edges extending across the cuff protector and adjacent to the meeting edges of the cuff.

100

3. A cuff protecting device including a sheet of material folded back upon itself to 115 constitute two protecting walls, between which a cuff may be interposed, hook mechanism adapted to engage the inner edge of the cuff, and extensible and contractible link mechanism uniting the hook mechanism and 120 the folded sheet, said link mechanism serving to press the cuff protecting device, where folded back upon itself, against the outer edge of the cuff, said cuff protecting device being thus afforded two places of anchorage 125 upon the cuff, namely, the outer edge of the cuff where the fold of the cuff protector is engaged and the inner edge of the cuff, where

the extensible and contractible link mechanism is engaged; the sheet of material being curved so as to be adapted to the shape of a cuff, the outer and inner layer of the cuff protector each having opposed meeting edges extending across the cuff protector and adjacent to the edges of the cuff.

In witness whereof, I hereunto subscribe my name this 12th day of October, A. D., 1907.

Correction in Letters Patent No. 879,955.

It is hereby certified that in Letters Patent No. 879,955, granted February 25, 1908, upon the application of Harry A. Frank, of Chicago, Illinois, for an improvement in "Cuff-Protectors," an error appears in the printed specification requiring correction, as follows: Page 3, line 5, the word "meeting" should be stricken out and inserted after the article "the" in line 7, same page; and that the said Letters Patent should be read with this correction therein that the same may conform to the record of the case in the Patent Office.

Signed and sealed this 24th day of March, A. D., 1908.

C. C. BILLINGS,

* Acting Commissioner of Patents.

the extensible and contractible link mechanism is engaged; the sheet of material being curved so as to be adapted to the shape of a cuff, the outer and inner layer of the cuff protector each having opposed meeting edges extending across the cuff protector and adjacent to the edges of the cuff.

In witness whereof, I hereunto subscribe my name this 12th day of October, A. D., 1907.
